United States Patent Office.

ALFRED FELLOWS, THOMAS B. HARRISON, AND HUGH DYER, OF MAQUOKETA, IOWA.

Letters Patent No. 73,962, dated February 4, 1868.

IMPROVEMENT IN LOOM-INDICATOR.

The Schedule referred to in these Letters Patent and making part of the same.

TO ALL WHOM IT MAY CONCERN:

Be it known that we, ALFRED FELLOWS, THOMAS B. HARRISON, and HUGH DYER, of Maquoketa, in the county of Jackson, and State of Iowa, have invented a new and useful machine, known as a Loom-Indicator, for measuring textile fabrics during their manufacture in the loom, also for registering the number of threads of weft in any given length of fabric woven; and we do hereby declare that the following is a full, and exact description thereof, reference being had to the accompanying drawings, making a part of this specification, in which—

Figure 1 is a front elevation.

Figure 2, a side elevation and section of case.

Figure 3, a front view with a part of the wheel-work removed.

Figure 4, a view of bevel-wheel, showing friction-plate and spring.

Figure 5, an end view of the measuring-wheel and driving-spur.

The construction of the machine is as follows: A represents a circular case, one side of which is perforated to receive the shaft B. On the outer end of this shaft is placed a cylinder or pulley, of wood, C, having its surface thickly studded with small sharp points or pins. This measuring-pulley is fitted loosely on the shaft B, and has on its inside face a pin or stud, D. Secured to the shaft B, in contact with the inner face of the pulley C, is a short lever or driving-spur E, the object being to allow free motion in either direction to the pulley, yet only communicating motion to the shaft B, in one direction, by the spur being driven forward by the pin D. On the other end of the shaft B is a bevel-wheel, F. This engages with the wheel G, of double its size and number of teeth. This wheel is attached to the centre arbor H, which passes through the dial K, carrying the longest hand L, indicating on the outer divisions of the dial. The pulley C is made exactly six inches in circumference, and the bevel-gears being made two to one, causing the centre arbor to make one revolution to two of the measuring-cylinder, and the hand L will indicate one foot, measured in each revolution, the divisions on that portion of the dial representing inches and fractions of an inch. In front of the two bevel-wheels, supported by the bridge M, are two ratchet-wheels, N and O. These ratchets are fastened to two hollow arbors or sleeves, revolving one within the other upon the centre arbor H, the ends of both passing through the dial K, and carrying the hands P and Q, the shortest of the hands, Q, being operated by the ratchet-wheel O, indicating on the inner circle of divisions on the dial, and the other hand, P, carried by the ratchet-wheel N, and indicating on the middle circle of divisions on the dial. The bevel-wheel G has on its face a projecting pin, R, shown in fig. 3. At each revolution of the wheel G the pin R lifts the lever S, and causes the pawl T to advance the ratchet-wheel N one tooth, indicating, by the hand P, feet and yards on the dial. The lever S is kept in contact with the lifting-pin R by means of the spring U. In order to prevent the pressure of the spring U and lever S from turning the hand P at certain points in the revolution of the wheel G, and to cause the hand to remain steady on the dial, the friction-device, shown at fig. 4, is used, and consists of a circular disk pressing on the surface of the wheel G by means of the spiral spring V. On the under side of the case is a bent lever, W, fig. 2, having its fulcrum at X. One end of this is fastened by means of a flexible cord to the lay or batten of the loom, and the other operates the pawl Y by means of the short rod Z, and lever A'' and spring B'', moving the front ratchet-wheel O one tooth for every beat of the loom, and registering on the inner circle of the dial the number of threads in any given amount of cloth woven. On the face of the ratchet-wheel O, near its centre, is a pin. This engages with the teeth of the gear-wheel K''. At each revolution of the ratchet-wheel O the pin moves the wheel K'' one tooth, carrying the small hand L'', indicating on the dial hundreds of threads or picks. The motion of the lever W is stopped at pleasure by means of the stop-button or lock C''. In order to set the hand carried by the wheel O, without opening the case, the milled-head knob F'' is provided on the outside of the case. This revolves the shaft E'', cog-wheel D'', and this, engaging with the teeth on the ratchet-wheel O, causes it to revolve, and sets the hand Q to any required starting-point.

The operation of the machine is as follows: It is secured to the "breast-beam" of the loom by means of the clamp-screw H'' in such a manner that the cloth, as it passes over the breast-beam to the cloth-beam, will

be in contact with the measuring-cylinder C. The movement of the cloth, as it is woven, is thus measured and registered on the dial by means of the hands L and P. When the operative wishes to know the texture of the fabric, the motion of lever W is stopped by turning the button C''. The hand Q is then set to a convenient starting-point by means of the knob F''; the position of the long hand L is carefully noted; then, by turning the button C'' and loosening the lever, a comparison of the relative positions of the hands will determine the number of threads in any given number of inches of cloth, thus enabling the operative to detect, at any time, any variation in the texture of the fabric, and to make the necessary adjustments of the weights, on the friction-belts, on the yarn-beam, to produce a fabric of uniform texture.

We claim as our invention—

1. The cylinder C, pin D, shaft B, and spur E, constructed, arranged, and operating as and for the purpose described.
2. The combination of the bevel-wheels G and F, arbor H, the ratchets O and N, with their hollow arbors, dial K, and hands P and L, arranged and operating as described.
3. The combination of the rod Z, lever A'', spring B'', lever W, pawl Y, and ratchet-wheel O, arranged and operating as described.
4. The shaft E'', button F'', and pinion D'', arranged and operating as above described.
5. Operating the lever W by means of a flexible cord attached to the lay or batten of the loom, as described.
6. The measuring-device, constructed as described, in combination with the clamp and screw H."
7. The combination of the wheel G, pin R, lever S, spring U, pawl T, and ratchet-wheel N, arranged and operating as described.
